CLAIM

The ornamental design for a drawer for a storage system, as shown and described.

DESCRIPTION

FIG. 1 is a perspective view of a drawer for a storage system, with upper rails and rollers for engaging a pair of carrying rails;

FIG. 2 is a top plane view of the design,

FIG. 3 is a bottom plan view of the design,

FIG. 4 is a left side view of the design,

FIG. 5 is a right side view of the design,

FIG. 6 is a front view of the design; and,

FIG. 7 is a rear view of the design.
